UNITED STATES PATENT OFFICE.

CHARLES J. McDONALD, OF SAN FRANCISCO, CALIFORNIA.

CHANGEABLE EXHIBITOR.

Application filed June 9, 1925. Serial No. 35,944.

To all whom it may concern:

Be it known that I, CHARLES J. McDONALD, a citizen of the United States, residing at San Francisco, in the county of 5 San Francisco and State of California, have invented certain new and useful Improvements in Changeable Exhibitors, of which the following is a specification.

My invention relates to manually changeable exhibitors, and more particularly to a 10 class of signs having interchangeable sliding plates.

Signs of the latter class are used a great deal in cafeterias, markets, automobile 15 agencies, and elsewhere. The sliding plate of the sign usually consists of a strip of white cardboard having printing thereon in black ink or paint, and the labor item in the preparation of the finished strip is the 20 expensive factor in such a temporary sign. If the sign is not executed in a neat or artistic manner it fails of its purpose and the expected trade is not drawn.

My invention has for an object the preparation 25 of strips in the form of stencils for the above purpose, and which strips in combination with a background of color contrasting with the color of the stencils form the sign plates. It is evident that stenciled 30 strips will always be executed in neat sharply defined characters by any operator of a stenciling machine, thus a further object is the production of such strips displaying signs of characters accurately and mechanically formed at a cost of but a fraction of 35 the heretofore produced strips.

A further object is to determine the legibility of my novel sign by the provision of simple means to effect contact of the stencil 40 with the colored background.

A still further object, in cases where a more expensive exhibitor is desired, is the provision of glass fronts for the individual stencils and which fronts may remain in the 45 racks as the stencils are removed and replaced by others. A simple means is provided to accomplish this retention of the glass, yet the glass may be removed easily when desired, as to clean it.

Other objects and advantages and the 50 features of construction of the invention, will appear in the subjoined description of the accompanying sheet of drawings in which:

Figure 1 is a face view of an exhibitor

constructed in accordance with my invention, and with only a couple of stencil signs shown in the racks for illustration purposes.

Fig. 2 is an edge view of Fig. 1.

Fig. 3 is a partial intermediate vertical 60 section of the device, and Fig. 4 is a similar view of an exhibitor with glass plates in front of the stencils; and

Fig. 5 is a full size view of a piece of 65 stencil as now used in the racks.

Adverting to the drawings I will now describe the figures thereof in detail, reference being had to numerals to indicate the elements of the invention. 6 denotes the backplate of the illustrated exhibitor and 70 the same may be a suitable board of wood having a smooth surface 7, the background for the stencils 8, and which background I prefer to coat with any suitable coloring for a purpose to be later set forth. 75

The stencils 8 are generally for temporary display and consist of strips of paper or cardboard of suitable color and stiffness, and have characters 9 perforated therethrough of the desired sign or notice. In some cases, 80 such as for the heading 10 of the exhibitor, I may wish to make the stencil of a more durable material and I find thin sheet metal satisfactory. I prefer to form the perforations 9 by a stenciling machine (not shown) 85 adapted to line, space and punch the characters at the will of the operator.

Surrounding the backplate 6 is secured a frame 11 of any desired shape, and transversely of the plate and between the frame 90 members is secured retaining racks 12 suitably spaced from one another to meet the purpose of the exhibitor under consideration.

The racks are rabbeted on their inner face 95 as shown at 13, and the depth of the rabbet is just sufficient to allow the stencil to slide freely within the rack and effect contact with the surface of the backplate. At one edge of the framed structure the racks may extend to the edge by tongues 14, and upon which the frame element 15 may be supported to form the entrance slots 16 for the narrow stencils and the slot 17 for the heading stencil 10. 100

On the backplate along the insertion edge of the exhibitor I provide indents or cutouts 18 about midway of each stencil for the entrance of the finger tip to slide the stencil out with ease, each stencil substan- 110

tially extending to the said outside edge as shown in Fig. 1 at the broken-away portion of the frame element 15.

In Fig. 4 an exhibitor is shown with a glass facing 19 in front of each stencil 8, the rabbet 20 being of a depth to snugly receive the glass and stencil and effect contact of the latter with the surface of the backplate and the glass.

10 The portion of the stencil illustrated in Fig. 5 was traced direct from the stencil and it exhibits the neat character of work done by the stenciling machine by any intelligent operator.

15 The exhibitor with racks occupied and ready for display presents a most attractive sign, harmonious in color scheme and easily readable, the whole produced at an extremely low expense.

20 From the foregoing description taken in connection with the accompanying drawings, the advantages of the construction and method of operation will be readily understood by those skilled in the art to which

25 the invention appertains, and while I have described the principle of operation, together with the device which I now consider to be the best embodiment thereof, I desire to

have it understood that the device shown is merely illustrative and that such changes 30 may be made, when desired, as fall within the scope of the appended claim.

Having thus described my invention, what I claim as new and desire to secure by Letters Patent of the United States is the following:

A changeable exhibitor comprising, a sign holder consisting of a framed structure having a smooth backplate and retaining racks on the plate, and stencils adapted to 40 be slid to position in the racks and substantially contact the smooth surface of the plate, the said surface having a color to contrast with the color of the stencils to effect the legibility of the stencils, and each of said 45 racks having a glass in front of and substantially contacting the stencil therein, said stencils extending from the inside of the frame at one side of the plate to the outside edge of the frame at the other side of the plate, and 50 the plate provided with means to facilitate the removal of the stencils.

In testimony whereof I affix my signature.

CHARLES J. McDONALD.
